CORNER BRACE FOR A METAL FORM UNIT

Lyde S. McCracken, Des Moines, Iowa, assignor to
Economy Forms Corporation

Filed May 30, 1974, Ser. No. 474,695

Term of patent 14 years

Int. Cl. D8—08

U.S. Cl. D54—1 R

FIG. 1 is a top perspective view looking toward one side of my new design for a corner brace for a metal form unit;

FIG. 2 is a front view;

FIG. 3 is an elevational view looking toward the side opposite the one shown in FIG. 1;

FIG. 4 is an elevational view looking toward the side shown in FIG. 1;

FIG. 5 is a rear view;

FIG. 6 is a top view; and

FIG. 7 is a bottom view.

I claim:

The ornamental design for a corner brace for a metal form unit, substantially as shown.
